UNITED STATES PATENT OFFICE.

JOHN W. COVER, OF ANDERSON, MISSOURI.

PIANO PEDAL-GUARD.

1,177,387.

Specification of Letters Patent. Patented Mar. 28, 1916.

Application filed September 15, 1915. Serial No. 50,830.

To all whom it may concern:

Be it known that I, JOHN W. COVER, a citizen of the United States, residing at Anderson, in the county of McDonald and 5 State of Missouri, have invented certain new and useful Improvements in Piano Pedal-Guards; and I do hereby declare the following to be a full, clear, and exact description of the invention, such as will enable 10 others skilled in the art to which it appertains to make and use the same.

This invention relates to new and useful improvements in pedal guards for pianos, and the principal object of the device is to 15 provide a device which will effectively prevent mice from entering a piano and injuring the interior mechanism thereof.

Another object of the invention is to provide a device which may be readily made 20 from sheet metal and which may be either stamped from a single piece of sheet metal, or which may be formed of a plurality of strips secured together in any suitable manner.

25 With these and other objects in view, the invention consists in the novel combination and arrangement of parts which will be fully set forth in the following specification and accompanying drawings, in which:—

30 Figure 1 is a perspective view of this improved guard, and Fig. 2 is a fragmentary sectional view through a portion of a piano, illustrating the guard attached thereto.

Referring now to the drawings by characters of reference, the numeral 1 designates 35 the piano body provided with the usual pedal opening 2. The pedals are designated by the numeral 3.

The attachment, which is connected to the 40 piano, comprises the base or body, designated generally by the numeral 4, which is formed of a strip of metal 5 having the arms 6 formed at each end, which arms extend outwardly therefrom, as clearly shown in 45 Fig. 1. A suitable ear 7 is formed centrally of the rear edge of the body and is provided with an opening 8 for the reception of an attaching screw, by which the device is secured to the under side of the piano. Connecting the free ends of the arms 6 is a suitable bottom bar 9 and a top bar 10, which are riveted to the arms 6, as at 11, and these arms and bars are provided with aligned 50 openings 12 for the reception of screws by

which the device is attached to the under 55 side of a piano.

Riveted at spaced intervals, as at 13, to the body 5, are the strips 14, the bowed ends of which pass between the bars 9 and 10 and are provided with the upward extensions 15 60 which are inturned at their upper ends, as at 16. These inturned upper ends are provided with the pads 17, which are preferably of rubber, felt or similar material, designed to prevent any noise of the engagement of the lower side of the pedal with the extensions 15. These strips 14 are preferably of a resilient material, so that when the pedal is pressed downwardly and returned to its uppermost position, the strip will follow 70 the movement of the pedal.

Extending through the strips 9 and 10 and spaced laterally of the strips 14, are suitable rivets 18, which hold the bars 9 and 10 in parallel relation. 75

It will be apparent from the foregoing that in use the device is secured to the underside of the piano, as illustrated in Fig. 2, and the extensions 15 close the openings beneath the pedals, as clearly shown. Upon 80 downward pressure upon one of the pedals, it will be seen that one of the strips will move downwardly, and when the pedal returns to its normal position, it will be apparent that the resilience of the strip will 85 cause the same to follow the pedals and thus keep the opening closed at all times.

While in the foregoing there has been shown and described the preferred embodiment of this invention, it is to be understood 90 that such changes may be made in the combination and arrangement of parts as will fall within the spirit and scope of the appended claims.

What is claimed is:—

1. A device of the character described comprising a bar, arms formed at the ends of the bar, bars connecting the arms, said bars being in spaced relation and secured to the first mentioned bar and extending between the last named bars, extensions at the ends of the strips to close the opening on the under sides of piano pedals when the 100 pedals are in their upward position. 105

2. A device of the class described comprising a frame, resilient strips pivotally secured at one end to said frame, upturned

extensions at the free ends of the strips, said extensions being adapted to engage the under side of a piano pedal to close the openings through which the pedal operates the resilience of the strips allowing the extensions to follow the pedals during their movements, the strips being pivoted to the frame to enable the distances between the extensions to be varied to accommodate pianos in which the distance between the pedals varies and means to limit the lateral movement of each strip.

3. A device of the class described comprising a bar, arms formed at the ends of the bar, bars connecting the outer ends of the arms, said bars being in spaced relation and secured to opposite sides of the arms, strips pivoted on the upper side of the first mentioned bar and extending between the last named bars, extensions at the ends of the strips to close the openings on the under sides of piano pedals, when the pedals are

in their upward position and means carried by the last named parallel bars to limit the lateral movement of the strips. 25

4. A device of the class described comprising a bar arms formed at the ends of the bar, bars connecting the outer ends of the arms, said bars being in spaced relation and secured to opposite sides of the arms, 30 strips pivoted on the upper side of the first mentioned bar and extending between the last named bars, extensions at the ends of the strips to close the openings on the under sides of piano pedals, when the pedals are 35 in their upward position, and rivets extending through and connecting the parallel bars to limit the lateral movements of the strips.

In testimony whereof I affix my signature in presence of two witnesses.

JOHN W. COVER.
